UNITED STATES PATENT OFFICE.

LEONIDAS L. TITTLE, JR., OF DAYTON, OHIO.

FUNNEL.

1,306,319.

Specification of Letters Patent. Patented June 10, 1919.

Application filed April 14, 1919. Serial No. 289,923.

To all whom it may concern:

Be it known that I, LEONIDAS L. TITTLE, Jr., a citizen of the United States, residing at Dayton, in the county of Montgomery and 5 State of Ohio, have invented certain new and useful Improvements in Funnels, of which the following is a specification.

This invention relates to packaging liquids, and more especially to funnels; and 10 the object of the same is to produce a measuring cup having a normally closed spout in its bottom, and manually operable means for opening said spout to convert the cup into a funnel.

15 The invention contemplates the employment of means on the body of the cup for measuring the contents as usual, and also it includes means for permitting the operation of opening the spout by movement of 20 the thumb when his fingers hold the handle.

Details are set forth in the following specification, and attention is invited to the drawings, wherein—

Figure 1 is a side elevation of this device 25 complete.

Fig. 2 is an enlarged vertical section looking toward the rear or handle side of the cup.

Fig. 3 is a cross section on the line 3—3 30 of Fig. 2.

In the drawings the numeral 1 designates a cup having a pouring lip 2 at its front side and a handle 3 at its rear side, and this cup is stamped with lines 4 with numerals 35 marked adjacent, so as to indicate the contents by the liquid level within the cup.

The numeral 5 designates legs depending from the bottom of the cup so as to hold it raised above a support such as a table top.

40 The numeral 6 designates a spout which preferably tapers downward slightly as shown, and is shorter than the legs 5 so that the latter will hold the tip of the spout off of the table or support. The bottom 1' of 45 the cup descends slightly from all sides toward its center as best seen in Fig. 2, and the upper end of the spout opens through the dropped center of this bottom at the point 6' and is secured thereto in any appropriate manner. Thus the liquid within 50 the cup will all run out the spout when the latter is open. Within its upper end is a valve in the shape of a rubber plug 7 which is preferably slightly conical as seen in Fig.

55 2 and of a size to fit closely in the upper end

of the spout when borne down into the same, and at this time the flow of the liquid from the cup is checked. Means are provided (as described below) for holding the plug normally in the position shown, and 60 while it remains there and closes the spout, the cup may be used in the ordinary manner, the lines 4 on its body being useful for measuring the contents in a manner well understood.

65 Fastened through or to the plug is an upright rod or stem 8 which, at a point just above the plug is carried horizontally and radially therefrom as seen at 8' in Fig. 3, until it reaches a point adjacent the wall of 70 the cup. Here it is given a right angular bend and carried then upward as at 8'' its upper end being formed into a loop or handle 12 standing adjacent the cup-handle 3. For guiding the main portion 8'' of this 75 rod, a piece of strap metal is secured to the back of the cup and bent forward at its upper and lower ends, the forwardly bent portion being pierced with eyes constituting guides 10 and 11 through which the rod 80 passes freely. Through the rod is a pin 14, above which a spring 13 is coiled upon the rod between the pin and the upper guide 11, and the expansive tendency of this spring 85 normally throws the rod downward and therefore normally keeps the valve or plug 7 within the upper end of the spout.

75 While the rod may have any appropriate cross section, I prefer to make it round, as shown. As a round rod might rotate with 90 in the guides 10 and 11 and therefore its arm 8' might throw the plug 7 out of alignment with the upper end of the spout, I employ means for preventing such rotation and such contingency. This consists in a rod or strip 95 of metal 9 curved to conform with the curvature of the wall of the cup 1, its midlength being formed into an eye 9' which embraces the upright portion 8'' of the rod and is fastened thereto in any appropriate manner. 100 In the present instance I have shown a pin 9'' passing through the eye and the rod 8'' although I do not consider this form of attachment absolutely necessary. The ends or arms of the element 9 slide upon the inner 105 face of the wall of the cup as the rod rises and falls, and therefore said rod cannot rotate within the guides 10 and 11. The result is that the plug 7 is always held directly in line with the axis of the spout 6.

In operation, the user grasps the main handle with the fingers of his hand and inserts his thumb through the loop 12 and the cup can now be used for measuring purposes or otherwise as desired. When occasion arises where the contents of the cup are to be delivered, as for instance into the mouth of a bottle having a rather small neck, the tip of the spout 6 is inserted into said mouth and the thumb is raised. This draws upward on the loop 12 and rod, and the rod causes the plug 7 to rise out of the upper end 6' of the spout, so that the contents of the cup runs out into the bottle or other receptacle. As soon as upward impulse on the thumb is relaxed or the thumb withdrawn from the loop 12, the spring acts to slide the rod downward through its guides and the arms of the strip 9 slide downward on the wall of the cup, so that the plug is reseated in the upper end of the spout and further flow of liquid from the cup is prevented.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claim.

Copies of this patent may be obtained for five cents each, by addressing the "Commissioner of Patents, Washington, D. C."

What is claimed as new is:—

In a device of the character described, the combination with a cup having a cylindrical body, its bottom descending from said body to the center and there having an opening, legs depending from the cup, a spout shorter than the legs and whose upper end engages said opening, and a main handle on the cup; of guides within the wall of the cup in line with its main handle, a rod slidably mounted through said guides and with its lower end carried radially inward over the bottom of the cup and turned downward, a plug secured to the down-turned end of the rod and adapted to close the upper end of the spout, a pin through the rod between said guides, an expansive spring coiled on the rod between the pin and the upper guide and normally seating the plug in the spout, a loop at the upper end of the rod, and a strip having an eye at its center rigidly mounted on the rod below the lowermost guide and having its arms curved to slide within the wall of the cup as the rod and plug rise and fall.

In testimony whereof I affix my signature in presence of two witnesses.

LEONIDAS L. TITTLE, JR.
